Mosler Safe Company, Hamilton, Ohio, a corporation of New York

Filed July 26, 1963, Ser. No. 75,983

Term of patent 14 years

(Cl. D69—1)

FIGURE 2 is another front perspective view thereof, the door being in an open position; and

The dominant features of my design reside in the portions shown in full lines.

I claim:

The ornamental design for a vault entrance, substantially as shown and described.
